(57) **CLAIM**

The ornamental design for an ultrasound scanner clip-on, as shown and described.

DESCRIPTION

FIG. 1 is a front perspective view of an ultrasound scanner clip-on in accordance with the present design;

FIG. 2 is a rear perspective view thereof;

FIG. 3 is a top view thereof;

FIG. 4 is a front view thereof;

FIG. 5 is a right side view thereof;

FIG. 6 is a left side view thereof;

FIG. 7 is a rear view thereof; and,

FIG. 8 is a bottom view thereof.

The broken lines in the figures represent portions of the article which form no part of the claimed design.
